UNITED STATES PATENT OFFICE.

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT.

STAPLING MACHINE.

Application filed September 25, 1924. Serial No. 739,782.

To all whom it may concern:

Be it known that I, FRIDOLIN POLZER, a citizen of the United States, residing at Norwalk, county of Fairfield, State of Connecticut, have invented a new and useful Stapling Machine, of which the following is a specification.

This invention relates to automatic stapling machines of the type in which a strip 10 of previously formed staples connected together are fed forwardly with a step by step movement into a position where the individual staples may be cut from the strip, driven and clinched by a movable plunger, and has for an object to provide a machine of this character which may be used for driving either long or short staples, and which when used for driving the short staples may be operated directly with a blow of the hand, as 20 in the ordinary stapling machines, but which is provided with a lever which may be used for driving the longer staples, thus giving greater power for the driving operation where it is desired to staple a large number 25 of sheets of paper together.

With the foregoing and other objects in view, I have devised the construction illustrated in the accompanying drawing forming a part of this specification, similar reference characters being employed throughout the various figures to indicate corresponding elements. In this drawing,

Fig. 1 is a partial side elevation and partial longitudinal vertical section of the device.

Fig. 2 is a top plan view thereof.

Fig. 3 is a partial end elevation looking from the right of Fig. 1 and partial section substantially on line 3—3 of Fig. 1.

Fig. 4 is a vertical longitudinal section 40 through the housing.

Fig. 5 is a detail section substantially on line 5—5 of Fig. 4, and

Fig. 6 is a rear elevation of the lower part 45 of the machine looking from the left of Fig. 1.

In the embodiment illustrated the machine comprises a base 10 having an upwardly extending lug 11 carrying the anvil 12 which 50 has the usual recesses in the top surface thereof for clinching the staples. This anvil is a steel plate removably mounted on the lug 11 by suitable screws 13. At the rear end of the base is another upwardly extending lug 14 which is embraced by the forked

lower end 15 of a bracket 16 and to which the bracket is secured by suitable pins 17, this bracket being curved forwardly as shown in Fig. 1, and preferably substantially U-shaped in cross section so that it 60 is open at its forward side.

The upper portion 18 of the lug 14 is somewhat narrower than the lower portion, as shown in Fig. 6, and is embraced by the projections 19 on the rear end of the housing 20, and the housing is pivoted to this lug by a pin 21 extending through these projections and the lug. The housing may be of any desired shape, but is preferably substantially that of the standard type of stapling machines of this character, and it encloses the staple strip guiding and holding means, the feeding means and the staple severing and clinching mechanism. The staple guiding and supporting means 65 comprises the usual slide 22 mounted in the lower part of the housing by pins or screws 23. The upper part of this slide, as is usual, is of slightly less width than the distance between the prongs of the staples 24 on the staple strip supported by this guide, and at its lower portion is somewhat wider or has spacing strips 25 to provide clearance for the staple prongs between the slide and the housing. The usual holdback 26 is pivoted in the housing 70 at 27 and is held against the top of the staple strip by a spring 28, this holdback preventing backward movement of the strip during the backward movement of the feed pawl 29. The feed pawl is pivoted to a cam 75 plate 30 pivoted in the housing at 31, and the pawl is normally held in engagement with the top of the staple strip by a spring 32, and the cam plate is swung about its pivot to advance the pawl and the staple strip by 80 means of a spring 33.

The forward portion of the housing is provided with the usual guides 34 for a vertically moving plunger 35, the lower end 36 of this plunger being arranged to coact with the forward end of the slide 22 to sever the individual staples from the strip, to then drive the prongs of the staples through the articles indicated at 37 to be connected, and then, in conjunction with the anvil, to clinch the staples. At the rear side of the plunger a cam lug 38 is arranged to engage the cam 39 when the plunger is forced downwardly, to rock the feed plate on its pivot and move the feed pawl backwardly to engage the next 100 105 110

staple on the strip preparatory to the next feeding operation when the plunger moves upwardly. A cross pin 40 is in the path of the movement of this lug 38 and limits the 5 upward movement of the plunger.

Closely adjacent the plunger and to the rear thereof is a plate 41 having downwardly extending fingers 42 on opposite sides of the lug 38 arranged to pass between 10 the prongs of the first and second staples on the strip to straighten these staples should they be bent out of the vertical position, and will also hold the first or foremost staple on the strip to prevent its turning 15 backwardly during the operation of severing this staple from the strip. This plate is movable with the plunger throughout a portion of its movement, but after the lower ends of the fingers 42 engage the top of the 20 articles 37 this plate has no further movement although the plunger may advance further to clinch the staples. This movement of the plate is controlled by means of coil spring 43 and 44 which embrace the projecting portion of the plunger above the housing, and the lower spring 43 also embraces this plate. At its upper end the plate is provided with flanges 46 engaging the opposite sides of the plunger whereby the plate 25 is guided by the plunger, and above these flanges is provided with outwardly and upwardly extending fingers 47. The upper end of the spring 43 rests against the under sides of these fingers so as to raise the plate 30 and the fingers 42 and also the plunger. A washer or disc 48 embraces the plunger and has an opening therethrough of substantially the same size and form as the plunger so that it may slide on the plunger but is rigidly held against lateral movement. This 35 disc is provided with notches 49 in which the fingers 47 of the plate 41 project, and this disc, therefore, prevents the plate 41 moving laterally away from the plunger should it meet with a too great resistance 40 against the staples during its downward movement. In other words, the washer retains the plate 41 in its proper position relative to the plunger. The upper spring 44 rests against the top of the disc and the under side of the cap or head 50 secured to the upper end of the plunger. The upper spring 44 is somewhat stiffer and stronger than the lower spring 43 so that as the plunger 45 is forced downwardly the lower spring will be compressed and the upper spring will force the plate 41 downwardly to insert the fingers 42 between the prongs of the staples. When the staple straightening device reaches its lowest position, as when the lower ends of the fingers 42 engage the top of the articles to be connected, the spring 44 will then allow the plunger to complete 50 its movement to clinch the staples.

65 Pivoted in the upper portion of the brack-

et 16 is an operating lever 51, the pivot being shown at 52, and this lever is normally in a substantially horizontal position, as shown in full lines Fig. 1, over the top of the plunger. This lever is also preferably 70 substantially U-shape in cross section to give it the required strength and also so that it will be open at its lower side. The upper side of the handle portion of this lever is rounded so that it will be comfortable to the hand of the operator. Mounted within this lever between the handle and pivot is means for engaging the head 50 of the plunger 35 for operating this plunger. This means preferably comprises an anti-friction roller 53 which will run on the top surface of the head when the lever is depressed, and it is preferably so arranged that the center line of this roller is substantially on the vertical center line of the plunger at the time when the lower end of the plunger engages the foremost staple on the strip to sever this staple from the strip. This is the position shown in dotted lines Fig. 4 and is the time when there is the greatest resistance to the movement of the plunger, and by arranging the elements thus there is no lateral strain on the plunger when it is in the position of greatest resistance. A spring 54 is enclosed by the bracket 16 and is connected at its opposite ends to this bracket and the lever 51 and tends to hold the weight of this lever off the top of the plunger so that the spring 43 does not have to raise this lever after the clinching operation, but merely is required to raise the plunger as in the usual type of stapling machines. A screw 55 or other suitable holding device is mounted in one side of the lever 51, and is arranged to engage under the head 50 on the plunger so that by raising the handle of the lever, as shown in dotted lines Fig. 1, this screw or catch will also raise the forward end of the housing 20 about its pivot 21 away from the anvil and allow insertion of the articles 37 which are to be stapled. This upward movement is limited by a stop pin 56 carried by the bracket in position to be engaged by the upper wall of the housing.

In stapling a large number of articles together, as for instance a large number of sheets of paper, considerable force is required to force the prongs of the staple through these articles, and it will be apparent that this lever as shown will give the required power for easily forcing the prongs through the articles, but as a large part of the work of machines of this type is to staple a small number of sheets at a time the lever 51 may be moved to an ineffective position to allow direct manual operation of the plunger with a blow of the hand on the head or cap 50. This is accomplished by retracting the screw 55 so that it will no longer engage under the head 50, and then the lever 51

may be raised to the dot and dash position 51', Fig. 1, to expose the head of the plunger. The lever will be held in this position by the spring 54.

5 It will be apparent from the above description that the lever 51 provides simple and powerful means for clinching the staples so that a large number of articles, as sheets of paper, may be easily stapled, 10 and that this lever also provides convenient means for lifting the housing carrying the stapling mechanism from the anvil to allow placing the articles in the stapling position. Furthermore, that by a simple 15 operation the lever may be moved to an ineffective position to allow direct manual operation of the plunger in the stapling of a small number of sheets, if desired. The staple strip is inserted in the machine onto 20 the slide 22 through the opening 57 at the lower part of the bracket 16.

Having thus set forth the nature of my invention, what I claim is:

1. In a stapling machine, a base, an an- 25 vil mounted on the base, a pivoted housing, a plunger mounted in the housing and adapted to coact with said anvil to set the staples, a pivoted lever, a connection between the lever and said plunger for operating the latter, and a connection between 30 the lever and housing for lifting the latter to permit insertion of articles to be connected between the housing and anvil, said lever being movable to an ineffective position to permit direct operation of the 35 plunger.

2. In a stapling machine, a base, a pivoted lever, a pivoted housing, a plunger mounted for up and down movement in 40 the housing for clinching the staples, a head on said plunger shaped for direct manual operation thereof by a blow of the hand, means for limiting the upward movement of the plunger, and an easily releasable connection between the lever and plunger to 45 operate the plunger and lift the housing, thereby permitting the connection to be readily released to allow removal of the lever to an ineffective position and permit 50 direct manual operation of the plunger.

3. In a strip staple machine, a base, a housing pivoted to the base, a movable plunger mounted in the housing for severing and driving the individual staples and 55 provided with a head for direct manual operation of the plunger, a bracket extending upwardly from the base, a lever pivoted to the bracket, a roller carried by the lever engaging said head to operate the 60 plunger, means in the housing to limit the

upward movement of the plunger, and detachable means carried by the lever to engage under the head and lift the housing.

4. In a strip staple machine comprising a housing, means in the housing for feeding and guiding the staple strip, a vertically movable plunger for severing and driving the individual staples, a slidable element at one side of the plunger and movable throughout part of its movement therewith to pass between the first and second staple on the strip to hold the first staple during the severing operation, and means embracing the plunger and slidable element to prevent separation of the latter 75 from the plunger.

5. In a strip staple machine comprising a housing, means in the housing for feeding and guiding the staple strip, a vertically movable plunger for severing and driving the individual staples, a slidable element at one side of the plunger and movable throughout part of its movement therewith to pass between the first and second staple on the strip to hold the first staple during the severing operation, and a disc embracing the plunger and having recesses for passage of a portion of said slidable element to prevent lateral separation thereof from the plunger.

6. In a strip staple machine comprising a housing, means in the housing for feeding and guiding the staple strip, a vertically movable plunger for severing and driving the individual staples, a head at the top of the plunger for operating the same, a slidable element at one side of the plunger and movable throughout part of its movement therewith to pass between two adjacent staples on the strip, said element being provided with upwardly extending fingers at its upper end, a disc embracing the plunger and provided with recesses to receive said fingers, a spring embracing the plunger between the disc and said head, and a spring embracing the plunger between said fingers and the housing.

7. In a stapling machine a base, a pivoted lever substantially U-shaped in cross section, a movable housing, a plunger mounted for movement in the housing for clinching the staples, a head on the plunger extending between the sides of the lever, means carried by the lever engaging the head for operating the plunger, and means carried by the lever engaging under the head for lifting the plunger and housing.

In testimony whereof I affix my signature.

FRIDOLIN POLZER.
